(57) **CLAIM**

The ornamental design for an RFID tag housing, as shown and described.

DESCRIPTION

FIG. 1 is a perspective view of an RFID tag housing;
 FIG. 2 is a top plan view thereof;
 FIG. 3 is a left side elevational view thereof, the right side elevational view is identical but symmetrically reversed;
 FIG. 4 is a bottom plan view thereof;
 FIG. 5 is a top plan elevational view thereof;
 FIG. 6 is a front elevational view thereof; and,
 FIG. 7 is a back elevational view thereof.
 The portions of the RFID tag housing illustrated in broken lines form no part of the claimed design.
